UNITED STATES PATENT OFFICE.

SAMUEL E. DUFF, OF BELLEVUE, PENNSYLVANIA.

RAILWAY SUBSTRUCTURE.

SPECIFICATION forming part of Letters Patent No. 740,106, dated September 29, 1903.

Application filed December 12, 1902. Serial No. 134,893. (No model.)

To all whom it may concern:

Be it known that I, SAMUEL E. DUFF, of Bellevue, Allegheny county, Pennsylvania, have invented a new and useful Railway Sub-
5 structure, of which the following is a full, clear, and exact description, reference being had to the accompanying drawings, forming part of this specification, in which—

Figure 1 is a top plan view, partly broken away, showing a railway-track structure constructed in accordance with my invention. Fig. 2 is a cross-section of the same. Fig. 3 is an enlarged cross-section of one of the girders with the rail in place. Fig. 4 is an enlarged side elevation of the same. Figs. 5 and 6 are detail views of the tie-piece. Figs. 7 and 8 are detail views of my preferred form of rail-clip, and Fig. 9 is a cross-sectional view showing a modified form.

20 My invention relates to railway substructures, and more particularly to the system described in my Patent No. 672,892, dated April 30, 1901, upon which I have filed a re-issue application, Serial No. 135,340.

25 The object of the present invention is to simplify the arrangement of the substructure and increase its strength and durability.

In the drawings, 2 2 represent the girders, which extend continuously beneath the rails. 30 These girders are of inverted-trough shape, with lower side flanges 3 3, which are preferably turned up slightly at their outer ends, as shown at 4, to increase their strength. I preferably form these girders with a flat upper bearing portion 5, which is slightly wider than the base of the rail 6, the sides of the trough thence extending downwardly, preferably in a curve, to the flange 3. The exact shape of these girders may, however, be varied within the scope of my invention. The girders are preferably formed of pressed-steel sections and the top and sides are provided with transverse depressions or recesses 7 and 8. These depressions are preferably arranged

45 one near one end of the girder-section, as at 8, and the other, 7, at an intermediate point, which is preferably such that when the girders are in place the tie-pieces 9 are spaced substantially equal distances apart. The

50 end portion 10 of the girder beyond the depression 8 is contracted, so that it will fit within the end of the next section, as indi-

cated at the left-hand portion of Fig. 1, where the broken-away girder is shown about to be slipped into place. The flanges of this reduced portion will fit below the flanges of the full-sized section, into which it is slipped. The depth of this depression at the top of the trough is at least as great as the thickness of the web of the tie-piece 9, so that the tie-piece 60 when in position is either flush with or slightly below the level of the top of the trough. The tie-piece, as shown in Figs. 5 and 6, consists of a channel with flanges 11, which are notched or cut away, as shown at 12, leaving end lugs or flanged portions 13, which fit into transverse slots 14 in the recess portion of the girder. The ends of the flange proper, 11, are preferably inclined to fit the inner faces of the girders. The cross-ties when fitted in position are held by the rails, which are secured to the girders by the clips 15. (Shown in Figs. 7 and 8.) Each of these clips is provided with a shank which is notched at 16 to provide an end lug 17, the outer end of the clip being bent into a hook 18, which is preferably provided with a struck-up rib 19. The clip may be formed of pressed steel, the rib being formed during the pressing operation. These clips are arranged in 80 pairs with the hooks engaging opposite sides of the rail-base, the shanks extending through pairs of slots 20 in the girder. In applying the clips their shanks are slipped through the slots 20 and the lugs 17 are then bent down into 85 approximately vertical position. As the lugs are thus bent they move over the face of the girder, and owing to the slight incline the hook portion is drawn firmly against the base of the rail. I preferably employ bent-in 90 pocket portions 21 on the girder, these pockets having bosses 22, over which the lugs 17 pass as they are bent into final position. These bosses or stops prevent the lugs from springing back and allowing the clips to 95 loosen. A clearance-space is provided in the slip-joint between the reduced end of the one girder and the end of the next in their side portions, so that in laying a track upon a curve the girder-sections may be inclined to each other in this curved portion of the track. The flat top of the reduced portion preferably fits neatly under the top of the next girder, the clearance being merely between the sides,

In laying the track the girders and tie-pieces are assembled, the tie-pieces acting as spacers to maintain the required gage. As the girders are laid their ends are lapped to form the slip-joint, and when a section of suitable length has been laid the rails are put in place, care being taken to have the rail-joints at an intermediate point and preferably about the center of the girder, where the joint occurs. The rail-clips are then inserted from opposite sides and their end lugs bent down over the bosses or stops, which hold them in place. The ballast may be used in any desirable way.

15 In Fig. 9 I show a modified form of the clip 15', in which the hook portion is extended to form a rail-brace 23, which extends between the base and head of the rail in the usual manner. In this case I preferably extend 20 the rib portion 19' up through the brace, as shown.

The advantages of my invention result from the simplicity of the structure and its connections and the continuous supports of the 25 rail, which prevent deflection. The girders are preferably about one-quarter of the ordinary rail length, thus allowing the rail-joint to be placed in the center of the girder. The shear between the rail ends is thus taken up 30 by the supporting-girders and necessity for the use of heavy splice-bars is avoided. The springing of the rail ends is prevented and the ballast can be easily and cheaply applied. The parts are of only three different kinds 35 and are duplicates except in those clips used at the rail-joints, where they will be slightly altered on account of the splice. The parts may be cheaply made from rolled or shaped material, and a strong and durable track 40 structure is afforded.

Many variations may be made in the form and arrangement of the parts without departing from my invention, since

What I claim is—

45 1. In railway substructures, a series of girders having interfitting slip-joints with side clearance to provide for curved portions of the track; substantially as described.

2. In railway substructures, girder-sections arranged end to end beneath the rails, and 50 channel tie-pieces, the side flanges of which enter slots in the girders; substantially as described.

3. In railway substructures, the girders arranged end to end beneath the rails, and transverse tie-pieces consisting of channels having their side flanges notched near the end to provide end lugs which fit in slots in the girders; substantially as described.

4. In railway substructures, a girder extending longitudinally beneath and parallel with the rail, a pair of oppositely-extending clips for each girder having bent lugs, and stops on the girders arranged to prevent back turning of the bent lug; substantially as described. 60

5. In railway substructures, a longitudinal girder having a transverse depression and a tie-piece consisting of a channel with its web lying in the depression and its side flanges 70 projecting down through slots in the girders; substantially as described.

6. In railway substructures, a series of girders with interfitting ends, said girders being of a fraction of the length of the ordinary rail-section, and having an intermediate tie-piece and another tie-piece adjacent to the reduced end which enters the end of 75 the next girder; substantially as described.

7. In railway substructures, a girder extending beneath and parallel with the rail, and having a pocket or depression, and a clip having a lug bent within the pocket or depression; substantially as described. 80

8. In railway substructures, a longitudinal 85 girder, and a clip therefor, said clip having an extension between the head and base of the rail, and acting as a rail-brace; substantially as described.

In testimony whereof I have hereunto set 90 my hand.

SAMUEL E. DUFF.
